(57) **CLAIM**

The ornamental design for a cable tester as shown and described.

DESCRIPTION

FIG. 1 is a front, top and right side perspective view of a cable tester showing my new design;

FIG. 2 is a front, top and right side perspective view in detached state of two components thereof;

FIG. 3 is a front, top, and right side perspective view of the first component of the cable tester;

FIG. 4 is a rear, bottom and left side view thereof;

FIG. 5 is a front view thereof;

FIG. 6 is a rear view thereof;

FIG. 7 is a left side thereof;

FIG. 8 is a right view thereof;

FIG. 9 is a top plan view thereof;

FIG. 10 is a bottom plan view thereof;

FIG. 11 is a front, top and right side perspective view of the second component of the cable tester;

FIG. 12 is a rear, bottom and left side view thereof;

FIG. 13 is a front view thereof;

FIG. 14 is a rear view thereof;

FIG. 15 is a left side thereof;

FIG. 16 is a right view thereof;

FIG. 17 is a top plan view thereof; and,

FIG. 18 is a bottom plan view thereof.

The broken lines shown in the drawings illustrate portions of the cable tester that form no part of the claimed design.

The claim is directed to the collective appearance of the cable tester, which is demonstrated in FIGS. 1 and 2.
